ROTARY IMPACT TOOL

Spencer B. Maurer, Cleveland, Ohio

Application October 1, 1949, Serial No. 119,141

17 Claims. (Cl. 192—30.5)

This invention relates to portable, power operated, impact wrenches and similar tools for driving bolts, nuts, screws, and the like or for applying an impact rotational torque to other objects, all such tools being hereinafter generically referred to as impact wrenches.

The usual tool of this character comprises three basic parts, namely, a prime mover, such as an air motor; a rotatable hammer driven by the prime mover and having a high moment of inertia; and a rotatable output or work shaft, including an anvil member adapted to be struck by the hammer for imparting a high torque to the output shaft. The hammer assembly is disengageable from the anvil member to permit the prime mover to rotate the hammer member freely for imparting a high angular momentum thereto, and a clutch mechanism which may comprise part of the hammer assembly is provided for repeatedly engaging and disengaging the rotating hammer assembly and the stationary anvil to apply the momentum of the hammer member to the anvil and to the output shaft. The clutch mechanism is also adapted to disengage the hammer assembly from the anvil when the resistance to rotation of the output shaft has stalled the prime mover, thereby permitting free rotation of the hammer assembly for again building up its angular momentum. This cycle of operation is repeated until the power to the prime mover is cut off, the rapidity of the cycles and the magnitude of the torque applied being dependent upon a number of factors, including the rotational resistance of the object to be driven, the construction and mode of operation of the clutch mechanism, the power and acceleration of the prime mover, and, in some instances, the type of driving connection between the prime mover and the hammer assembly.

The principal problems involved in producing an impact wrench that is rugged and reliable and is efficient in operation and not too expensive to manufacture have centered around the clutch mechanism. Because of the operating precision required of the clutch mechanism and the large mechanical forces imposed upon it, this basic part of the impact wrenches has given rise to most of the difficulties with which the art has been faced. The many clutch designs for tools of this character that have been used, or made for use, differ widely in character. However, all those in commercial use of which I am aware rely upon centrifugal force or motor torque, acting directly through some form of mechanical linkage including cams, springs, and similar mechanical elements, for engaging and disengaging the clutch.

The principal object of this invention is to provide an improved rotary impact wrench in which operation of the clutch is effected in a more reliable and simple manner than has heretofore been achieved.

More particularly, it is an object of the invention to provide a rotary impact wrench in which actuation of the clutch is effected, at least in part, by fluid pressure.

A further object of the invention is to provide a rotary impact wrench adapted to be driven by a fluid pressure motor, such as an air motor, and in which fluid under pressure is employed for the dual function of driving the motor and controlling the clutch.

A characteristic feature of the invention, as illustrated herein, is the employment of fluid pressure in the clutch mechanism for effecting at least one of the two principal automatic clutch movements by which the hammer assembly and the anvil are engaged and disengaged. The advantages of the invention are best realized, of course,

2

when the prime mover of the impact tool is powered by fluid under pressure and a portion of the fluid supplied for that purpose is by-passed to the clutch mechanism for actuating the clutch mechanism. While numerous mechanical arrangements may be employed for utilizing fluid pressure to operate the clutch, the invention, in its broadest aspects, will be understood from the following description of two illustrative embodiments of the invention and from the accompanying drawings in which:

Figure 1 is a side elevation of a rotary impact wrench, partly in section, showing the relationship between the motor, the hammer assembly and associated clutch, and the output shaft and its associated anvil;

Figure 2 is a vertical section through the impact wrench as indicated by the line 2—2 in Fig. 1;

Figure 3 is another vertical section through the impact wrench as indicated by the line 3—3 in Fig. 1;

Figure 4 is a fragmentary, vertical, longitudinal section of the impact wrench showing a portion of Fig. 1 on an enlarged scale with certain parts in positions which they occupy at a different stage in the cycle of operation of the device;

Figure 5 is still another vertical section through the impact wrench as indicated by the line 5—5 in Fig. 1;

Figure 6 is a fragmentary vertical section similar to Fig. 4, showing a second embodiment of the clutch mechanism;

Figure 7 is a vertical section through the mechanism of Fig. 4, as indicated by the line 7—7 in Fig. 4; and

Figure 8 is a fragmentary, vertical, longitudinal section showing a portion of Fig. 6 with certain parts in positions which they occupy at a different stage in the operation of the device.

Referring first to the embodiment of the invention shown in Figs. 1 to 5, there is shown a rotary impact wrench embodying a conventional air motor and a new and improved clutch mechanism, a portion of the fluid under pressure (in this case, compressed air) normally supplied to the tool for driving the motor being by-passed to the clutch mechanism, where it is employed to effect both automatic and cyclic engagement and disengagement of the hammer assembly and anvil. Centrifugal force is employed to assist in the control of the clutch, but solely for operating a simple valve in the compressed air system. The primary forces responsible for operation of the clutch are applied to the mechanism entirely by compressed air, in a manner that will become more apparent as the description of this device proceeds.

As shown in Fig. 1, the tool is mounted in a housing that may conveniently comprise an integral handle and motor housing section 10 and a separate housing section 11 containing or mounting the parts of the device driven by the motor. The two housing sections 10 and 11 may be suitably flanged and secured together in any convenient manner.

The motor, the controls therefor, and the compressed air supply line leading to the motor may, for the most part, be of any conventional design and need not be described in detail. Essentially, this portion of the device includes a coupling 12 for a compressed air hose 13 that leads into the handle portion of the housing section 10 and to a main control valve contained therein (not shown). A trigger 14 is mounted on the handle portion for actuating the main control valve, from which a main air conduit 16 leads toward the motor.

For the purpose of illustration, the motor shown in the drawing is a commonly used, reversible, air motor of the vane type wherein the direction of rotation of the motor may be controlled by a valve 17 interposed between the main air conduit 16 and the motor for controlling, in a well known manner, the supply of air selectively either to the manifold 18 (for counter-clockwise rotation of the motor as viewed in Fig. 2) or to the manifold 19 (for clockwise rotation of the motor). The air enters the cylindrical rotor chamber 21 either through the ports 22 or the ports 23, drives the rotor by pressure on the vanes 24, and is exhausted through the exhaust port 26 and exhaust conduit 27 into a vented portion of the housing (not illustrated). The rotor 28 is eccentrically mounted in the rotor

chamber, and the vanes 24 are slidably mounted in radial slots in the rotor and are urged outwardly against the rotor chamber by air pressure in a manner not shown. The air entering the rotor chamber between each adjacent pair of vanes moves the vanes about the rotor axis in the direction to enlarge the space therebetween and permit expansion of the air as it travels toward the exhaust port 26. The valve 17 that controls the direction of rotation of the rotor is manually rotated about its axis by means of the lever 29 between 10 the position shown in the drawing and a second position 90° from the illustrated position.

The rotor 28 is preferably provided with integrally formed, oppositely projecting, hollow shafts 31 and 32 that are respectively mounted for rotation in ball bearings 33 and 34 carried by the housing section 10. The rotor assembly and bearings are held in place by an externally threaded ring 36.

The output shaft 37 is journaled in a bushing 38 carried by the housing section 11, and terminates at one 20 end in a suitable work driving tip 39. The bushing 38 is sufficiently long to hold the output shaft 37 firmly in alignment with the axis of the rotor 28 and to permit the clutch assembly to be supported solely by and between the output shaft and the hollow rotor shaft 32, 25 in a manner hereinafter described. The output shaft is provided with a circumferential shoulder portion 41 for retaining the shaft in the bushing 38. A radial projection 43 from the shoulder portion 41 of the output shaft constitutes an anvil 43 and is shaped on opposite 30 sides to provide identical impact surfaces 44 against which a hammer pin or impact delivering element may strike to drive the output shaft in either direction about its axis.

The clutch assembly is constructed around a relatively massive, hollow hammer member 47. One end of this member surrounds the rotor shaft 32 and is keyed thereto to provide a driving connection therebetween. The opposite end of the hammer member 47 surrounds the inner end portion 42 of the output shaft with a 40 close running fit to permit relative rotation of the hammer member and output shaft while preventing any rapid escape of air therebetween.

A heavy hammer pin or impact delivering element 48 is mounted for longitudinal sliding movement in an aperture drilled through the member 47 in a direction parallel to its axis and spaced radially outwardly therefrom. The pin 48 is adapted to be projected axially into the path of the anvil 43 for driving it in either direction about its axis as determined by the direction of rotation of the motor, and to be withdrawn to permit acceleration of the hammer member after rotational resistance of the output shaft has stalled the motor or has slowed it down nearly to a stalling condition.

To control the axial movement of the hammer pin 48, a reciprocable member or piston 51 having an enlarged forward end portion 52 is mounted in the hammer member 47 with the forward end portion 52 having a relatively close running fit therein and the rearward end portion 53 projecting with a close running fit into the hollow rotor shaft 32. The reciprocable member 51 is provided with an axial bore 55 extending from end to end thereof and is mounted in the hammer member 47 for axial sliding movement with respect thereto. The clearance between the piston 51 and both the hammer member 47 and the hollow rotor shaft 32 is maintained as small as possible to prevent rapid escape of air therebetween. The travel of the piston is limited in one direction by contact of the forward end thereof with the inner end surface 45 of the output shaft (Fig. 1). Its travel in the opposite direction is limited by an internal shoulder 56 of the hammer member 47 (Fig. 4).

The piston 51 and the hammer pin 48 are constrained to travel together as one body by a valve rod 57 that extends through aligned apertures therein. The axis of the valve rod 57 passes through the axis of the hammer member 47 in a direction normal thereto, and the valve rod is mounted for limited sliding movement along its own axis between the two extreme positions illustrated in Figs. 1 and 4. Within the piston 51, the valve rod 57 is provided with a portion 58 of enlarged diameter that serves as a valve in the central bore 55 of the piston for controlling the passage of fluid therethrough, as hereinafter described. Within the hammer pin 48, one end of the rod 57 is provided with another portion 59 of enlarged diameter that terminates in a head por-

tion 60. The head portion 60 of the valve rod 57 contacts the hammer pin 48 for limiting movement of the valve rod in one direction, as is most clearly shown in Fig. 5. The other end of the valve rod 57 has a weight 61 mounted thereon and held against removal by any suitable fastening means, such as a snap ring 62. The hammer member 47 is slotted at 63 and 64 to accommodate the valve rod 57 and permit it to travel longitudinally thereof together with the piston 51 and hammer pin 48. The valve portion 58 of the valve rod 57 has an annular surface 67 that is constantly exposed to the pressure of fluid in the axial bore 55 which tends to urge the valve rod toward the extreme position shown in Fig. 4.

Fluid for operating the clutch mechanism is conducted thereto from a branch conduit 71 that may conveniently be integrally formed in the housing section 10 with one end in open communication with the main air conduit 16 and its opposite end in communication with the small chamber 72 through one or more openings 75. A tube 73 extends at one end into the chamber 72, where it is held by a suitable sealing ring 74 of rubber or the like, and the opposite end of the tube 73 projects with a close running fit into the hollow rotor shaft 31. Thus, fluid at the main line pressure of the motor intake manifold is always freely admitted through the conduit 71, chamber 72, and tube 73, into the hollow rotor shaft, and thence through the axial bore 55 of the piston 51 as far as the valve portion 58 of the valve rod 57. A small cut-away portion 68 of the bore of the piston 51 permits the fluid to flow freely into contact with the annular surface 67, when the valve rod 57 is in the position shown in Fig. 1. This cut-away portion 68 may be formed by means of a drill run through the opposite side of the piston, the hole through the piston wall being subsequently filled by a plug 69.

When the trigger 14 of the impact wrench is actuated to admit air to the motor and to the clutch mechanism, the clutch mechanism is normally in the position shown in Fig. 4. As the hammer member 47 is rotated by the motor, the weight 61 on the valve rod 57 is subjected to the action of centrifugal force tending to move the rod 57 to the position shown in Fig. 1. At the same time, air under pressure in the axial bore 55 of piston 51 exerts pressure on the annular surface 67 of the valve portion of the valve rod, thus tending to hold the rod in the position shown in Fig. 4. When the rotary speed of the motor and the hammer member 47 reach the point where the centrifugal force on the weight 61 exceeds the force of fluid pressure on the annular surface 67, the valve rod 57 is caused to move with a snap action toward the position shown in Fig. 1. This movement causes the valve portion 58 of the rod 57 to close the axial bore 55 of the piston 51 and open the vent passage 76, and the fluid pressure exerted on the rearward end of the piston 51 causes it to move toward the output shaft 37. The hammer pin 48 moves with the piston 51 and is projected into the path of rotation of the anvil 43. When the hammer pin 48 strikes one of the impact surfaces of the anvil 43, it drives the anvil and the output shaft 37 until rotational resistance afforded by the object to which the impact wrench is applied reaches a magnitude sufficient to stall or nearly stall the motor.

When the motor approaches a stall in the course of driving the output shaft, there is no longer any appreciable centrifugal force acting upon the weight 61. As a result, the pressure on the annular surface 67 causes the valve rod 57 to move back to the position shown in Fig. 4. This opens the axial bore 55 of the piston and permits fluid to flow therethrough and out of the forward end 52 of the piston into the space between this end of the piston and the rearward end surface 45 of the output shaft 37. The total area upon which the fluid exerts its pressure at this end 52 of the piston 51 is substantially greater than the limited area upon which the fluid exerts its pressure at the opposite end 53 of the piston. As a result, the piston is driven rearwardly (to the right as viewed in Fig. 1) by the fluid from the position shown in Fig. 1 to the position shown in Fig. 4. Being constrained to move with the piston 51, the hammer pin 48 is thereby withdrawn from the path of rotation of the anvil 43, and the motor is again free to accelerate the clutch mechanism. When the speed of rotation of the clutch mechanism again reaches the point where centrifugal force on the weight 61 is sufficient to move the valve rod 57 back

to the position shown in Fig. 1, the hammer pin 48 is projected into the path of the anvil 43, as before, for delivering another driving blow. In order for air to escape from between the output shaft 37 and the end 52 of the piston 51 as the piston drives the hammer pin into the path of the anvil 43, a fluid passage 76 is provided in the enlarged forward portion 52 of the piston 51. When the clutch is in the position shown in Fig. 4, this fluid passage 76 is closed by the valve portion 58 of the valve rod 57. When the rod 57 is actuated by centrifugal force acting on the weight 61, however, the valve portion 58 of the rod 57 uncovers the passage 76 and permits fluid to flow therethrough and escape into a vented portion of the housing and out through a vent passage 77, thus relieving the pressure between the output shaft 37 and the piston 51.

When the motor is stalled or nearly stalled, the fluid pressure in the main air conduit 16 adjacent the motor intake manifold is at a maximum value determined by the pressure supplied to the impact wrench through the air hose 13. This insures that the pressure employed to disengage the hammer pin from the anvil is sufficient to accomplish that purpose. Similarly, when the motor is stalled or nearly stalled, the pressure in the axial bore 55 of the piston 51 is adequate to move the valve rod 57 from the position shown in Fig. 1 to the position shown in Fig. 4 for admitting the fluid under its maximum pressure through the balance of the axial bore of the piston and out of the end 52 thereof for driving the piston and the hammer pin from the positions shown in Fig. 1 to the positions shown in Fig. 4.

A particular advantage of this type of clutch lies in the fact that actuation of the clutch is responsive not only to the speed of the motor but also to the torque output of the motor for effecting both engagement and disengagement of the clutch solely by fluid pressure rather than by a torque responsive mechanical linkage. In other words, the clutch is actuated directly by fluid pressure in timed relationship to motor speed and torque. So long as the pressure in the air hose 13 is sufficient to rotate the motor, positive actuation of the clutch mechanism is insured, and it is unnecessary to rely for this action upon any type of mechanical springs, or upon any type of torque responsive mechanical linkage, both of which have been a common source of trouble.

It will be apparent from the foregoing description of the operation of the clutch mechanism that the impact wrench is admirably adapted for delivering a series of sharp hammer blows on the anvil of the output shaft as rapidly as the motor is capable of accelerating the freely rotatable clutch mechanism to the speed required for projecting the hammer pin into the path of the anvil.

One characteristic of a centrifugal valve control of this type is that once the valve rod starts to move in either direction the balance of forces tending to cause that motion are increased providing, in effect, a snap action. As the rotational speed of the clutch increases the air biasing force acting on shoulder 67 of the valve rod 57 decreases, the centrifugal force acting on the weight 61 increases and once motion of the valve rod starts at any given speed the centrifugal force increases due to the increased distance of the center of gravity of the weight 61 from its center of rotation. Before the valve rod can shift in the opposite direction the speed must be drastically reduced because the weight 61 has its maximum centrifugal force at its outward starting position. As the speed of the tool decreases, the air pressure bias acting on shoulder 67 increases until the inward motion of the valve rod starts at which time the rod snaps to its inward position. This means that the tool will rapidly spin nuts down to a seated position before the impact mechanism will begin to operate. This greatly reduces overall nut-running time.

Turning now to the embodiment of the invention illustrated in Figs. 6 to 8, there is shown in these figures a somewhat simplified clutch mechanism in which fluid pressure is employed solely for disengaging the clutch and a mechanical spring is employed for engaging the clutch. Except for differences in the design of the clutch itself, this embodiment of the invention may employ the same general housing and motor arrangement as in the first embodiment of the invention, described above. Accordingly, only the modified clutch mechanism and associated output shaft are illustrated in Figs. 6 to 8.

In this embodiment of the invention, the hammer

member 100 comprises a relatively simple, but massive, member having an axial bore of uniform diameter substantially from end to end thereof. One end of the hammer member 100 surrounds the motor shaft 32 and is keyed thereto for rotation therewith. The opposite end of the hammer member 100 surrounds an inward extension of the output shaft 101 with a free running fit.

In this case, the output shaft includes an integrally formed anvil 43 identical with that in the first embodiment of the invention, and an integrally formed shaft portion 102 that extends completely through the hammer member 100 and into the hollow motor shaft 32 with a close running fit. Approximately midway between the ends of the hammer member 100, the portion 102 of the output shaft is grooved circumferentially, as indicated at 103, and is drilled through on a diameter, at 104, and longitudinally along its axis, at 106, to provide for flow of fluid from the hollow motor shaft 32 into the groove 103.

20 An impact delivering element 107 is mounted for limited axial movement in the hammer member 100, as in the first embodiment of the invention, but in this case the rearward end of the impact delivering element is enlarged to form an annular piston surface 108 against which fluid under pressure may act. The aperture in the hammer member 100, in which the impact delivering element 107 is mounted, is similarly enlarged to accommodate this portion of the impact delivering element and to form a pressure cylinder 109. Fluid under pressure from the groove 103 is freely admitted into the cylinder 109 and against the annular surface 108 through an aperture or port 110 therebetween.

A spring chamber 115 is partially closed at its rearward or inner end by a perforated disk 111 held in place by an expanding lock ring 112. The adjacent end of the impact delivering element is provided with a cup portion 113 that accommodates a compression spring 114. The spring 114 bears at its opposite ends against the disk 111 and the end of the impact delivering element 107.

40 The clutch mechanism of Figs. 6 to 8 performs the same ultimate function, according to the same cycle of operation, as the clutch in the first embodiment of the invention. When the motor is stalled, the fluid pressure within the tool is at a maximum since the air consumption by the motor is at a minimum. This pressure is transmitted through the axial bore 106 and diametrical bore 104 in the shaft extension 102, through port 110 in the hammer member 100, and acts against the annular piston surface 108. The strength of the spring 114 is selected so that the fluid pressure at its maximum value is ample to compress the spring and hold the clutch in its disengaged condition illustrated in Fig. 8. As the motor accelerates, the fluid pressure at the clutch drops and the spring overcomes the pressure of the fluid on the annular piston surface 108, thereby projecting the impact delivering element again into the path of the anvil for delivering another blow thereto. When the rotary resistance of the object being turned again stalls, or nearly stalls, the motor, the cycle is repeated.

60 It will be noted in the foregoing descriptions of the operation of both embodiments of the invention that disengagement of the clutch is stated to occur when the motor is stalled or nearly stalled. Under most conditions of operation, the resistance of the work to rotation by the wrench will quickly and completely stop rotation of the motor in the driving direction after engagement of the clutch, and disengagement will normally occur while the motor is fully stopped or rebounding in the opposite direction. However, as long as the resistance of the work to rotation is small, as during the free running of a nut onto a bolt, the clutch will remain engaged after the first impact is received from the hammer. If the resistance of the work to rotation then builds up gradually, the motor speed will be gradually reduced and the fluid pressure in the bore 55 in the first embodiment and in the bore 106 in the second embodiment will slowly build up to a point sufficient to disengage the clutch before the decelerating motor has completely stopped.

75 This is a desirable effect, since it permits the motor quickly to accelerate again and a second blow to be struck with a minimum of delay, thus maintaining a maximum average speed of rotation of the work while resistance to rotation is relatively low and a considerable number of rapid revolutions of the work is desired.

80 While disengagement of the clutch does not necessarily

require complete stalling of the motor, satisfactory operation under all conditions requires that the clutch actuating mechanism be capable of disengaging the clutch when the motor does stall and friction in the mechanism is greatest, as will often occur when resistance of the work to rotation is substantially greater than the maximum torque the motor can develop. It is, therefore, entirely accurate to state that the clutch actuating mechanism is responsive to stalling of the motor for disengaging the clutch. However, as mentioned above, the rebound of the hammer may actually cause some slight turning of the motor in the reverse direction when a driving blow is struck, and disengagement of the clutch may occur during the rebound. In any event, disengagement of the clutch will always occur only after the motor has been slowed down to the point where the momentum of the hammer no longer materially adds to the output torque of the motor. This condition is referred to in the appended claims by stating that the motor is "substantially stalled," and it is intended that the expression be so construed.

From the foregoing disclosure of two embodiments of the invention, it should be apparent to those skilled in the art that many variations thereof can readily be devised. For example, referring to Figs. 6 to 8, the same principles involved therein can obviously be applied to engage the clutch by fluid pressure, as by employing variations in the motor exhaust pressure, and to disengage it by spring pressure. Also, while I have shown and described specific embodiments of the invention in which the fluid pressure is exerted upon a conventional piston, it is obvious that equivalent mechanism may be substituted, such as diaphragms and bellows. In the appended claims, the term "reciprocable member" is employed as a generic term embracing both a piston and its various equivalent mechanical elements. Accordingly, the scope of the invention is not intended to be limited to the particular mechanical arrangements disclosed except to the extent required by the terms of the appended claims.

Having described my invention, I claim:

1. In a rotary impact tool having a fluid pressure driving motor and a source of fluid pressure for operating the same; a rotatable output shaft having impact receiving surface means; a rotatable hammer assembly having impact delivering surface means driven by said motor for intermittent engagement with said impact receiving surface means to deliver a rotary blow to said impact receiving surface means, expandable fluid pressure chamber means, conduit means connecting said source of fluid under pressure to said fluid pressure chamber means for supplying thereto fluid under pressure to establish a force to expand said chamber means, means operating automatically to increase fluid pressure in said chamber means in response to substantial stalling of said hammer assembly and expand said chamber means with a force which is greater than and increases with increases of the frictional forces set up by the torque of said fluid pressure motor which frictional forces oppose expansion of said chamber means, and a connection between at least one of said impact surface means and said chamber means to produce relative disengaging motion between said impact receiving and delivering surface means when said chamber means expands.

2. In a rotary impact tool having a fluid pressure driving motor and a source of fluid under pressure for operating the same; a rotatable output shaft having impact receiving surface means substantially parallel to the axis of rotation thereof; a rotatable hammer assembly having impact delivering surface means substantially parallel to the axis of rotation thereof driven by said motor for intermittent engagement with said impact receiving surface means to deliver a rotary blow to said impact receiving surface means, fluid pressure chamber means in said tool which can be expanded by fluid pressure, conduit means connected to said source and to said fluid pressure chamber means for supplying thereto fluid under pressure to cause said chamber means to expand, centrifugally operable valve means operating automatically to increase fluid pressure in said chamber means and expand said chamber means, and a connection between at least one of said impact surface means and said chamber means to produce relative motion between said impact receiving and delivering surface means when said chamber means expands.

3. In a rotary impact tool having a fluid pressure

driving motor and a source of fluid under pressure for operating the same; a rotatable output shaft having impact receiving surface means; a rotatable hammer assembly having impact delivering surface means driven by said motor for intermittent engagement with said impact receiving surface means to deliver a rotary impact blow, fluid pressure chamber means in said tool which can be expanded by fluid pressure, conduit means connected to said source and to said fluid pressure chamber means, centrifugally operable valve means mounted for rotation with said hammer means for controlling flow of fluid through said conduit to control the fluid pressure in said chamber means and operable to decrease pressure in said chamber means when said hammer assembly rotates at a given high speed and operable when said hammer assembly is substantially stalled to increase fluid pressure in said chamber means to establish a force to cause said chamber means to expand, and a connection between at least one of said impact surface means and said chamber means to produce relative disengaging motion between said impact receiving and delivering surface means when said chamber means expands.

4. In a rotary impact tool having a driving motor; a rotatable output shaft having impact receiving surface means, a rotatable hammer assembly having impact delivering surface means driven by said motor for intermittent engagement with said impact receiving surface means to deliver a rotary impact blow, fluid pressure chamber means in said tool which can be expanded by fluid pressure, centrifugally operable valve means mounted for rotation with said hammer means for controlling the fluid pressure in said chamber means operable to decrease pressure in said chamber means when said hammer assembly rotates at a given high speed, fluid bias means continually exerting a bias force on said valve means in the direction opposite to the direction of centrifugal force on said valve means to move said valve means when said hammer assembly is substantially stalled to increase fluid pressure in said chamber means to establish a force to cause said chamber means to expand, and a connection between at least one of said impact surface means and said chamber means to produce relative disengaging motion between said impact receiving surface means and said impact delivering surface means.

5. In a rotary impact tool having a fluid pressure driving motor and a source of fluid under pressure for operating the same; a rotatable output shaft having impact receiving surface means, a rotatable hammer assembly having impact delivering surface means driven by said motor for intermittent engagement with said impact receiving surface means to deliver a rotary impact blow, expandable fluid pressure chamber means connected to said source of fluid, automatic control means operative when said hammer assembly is substantially stalled to increase fluid pressure in said chamber means to cause said chamber means to expand to establish a disengaging force, and a reciprocable member connected to at least one of said impact surface means responsive to the expansion of said chamber means to cause relative disengaging motion between said impact surface means, and means exerting a continuous engaging force on said reciprocable member in a direction opposite to the direction of said disengaging force and of a magnitude less than the peak magnitude of said disengaging force.

6. In a rotary impact tool having a fluid pressure driving motor and a source of fluid under pressure for operating the same; a rotatable output shaft having impact receiving surface means, a rotatable hammer assembly having impact delivering surface means driven by said motor for intermittent engagement with said impact receiving surface means to deliver a rotary impact blow, expandable fluid pressure chamber means connected to said source of fluid, automatic control means operative when said hammer assembly is substantially stalled to increase fluid pressure in said chamber means to cause said chamber means to expand to establish a disengaging force, and a reciprocable member connected to at least one of said impact surface means responsive to the expansion of said chamber means to cause relative disengaging motion between said impact surface means, and means responsive to fluid pressure exerting a continuous engaging force on said reciprocable member in a direction opposite to the direction of said dis-

engaging force and of a magnitude less than the peak magnitude of said disengaging force.

7. In a rotary impact tool having a driving motor; a rotatable anvil, a rotatable impact delivering element driven by said motor for striking and driving said anvil, actuating means including fluid pressure actuated means and a centrifugally operated valve for moving said impact delivering element into engagement with said anvil when said valve is rotating at a predetermined speed and fluid bias means continually exerting a bias force on said valve in the direction opposite to the direction of centrifugal force on said valve for moving said impact delivering element out of engagement with said anvil when said valve is rotating at a predetermined lower speed.

8. A rotary impact tool comprising a frame, a rotatable work member and rotatable driving means therefor mounted on said frame for rotation relative to the frame, an impact receiving element through which torque forces may be transmitted to said work member, an impact delivery element driven by said driving means and movable into and out of the path of rotational travel of said impact receiving element for respective engagement with and disengagement from said impact receiving element, a piston member reciprocably mounted in said rotatable driving means for actuating said impact delivery element, said piston member comprising two piston heads arranged one at each end of the piston member, one of said piston heads having a greater face area than the other, a fluid pressure chamber at one side of the piston having the greater face area, a fluid pressure supply chamber at one side of the piston having the lesser face area, a fluid pressure supply conduit in said piston member through which fluid under pressure may flow from said supply chamber to the first mentioned chamber, an exhaust conduit in said piston leading from the first mentioned fluid pressure chamber through which fluid may be vented from the chamber to the atmosphere, valve means operable to one position for permitting the flow of fluid through said fluid pressure supply conduit from said fluid pressure supply chamber to the first mentioned chamber and for preventing the flow of fluid from the first mentioned chamber through said exhaust conduit to the atmosphere and said valve means being operable to another position for cutting off the flow of fluid to the first mentioned chamber and for opening said exhaust conduit to permit fluid under pressure in the first mentioned chamber to flow to the atmosphere, and a centrifuge rotatable by said rotatable driving means and operable to control the operation of said valve means.

9. A rotary impact tool comprising a frame, a rotatable work member and rotatable driving means therefor mounted on said frame for rotation relative to the frame, an impact receiving element through which torque forces may be transmitted to said work member, an impact delivery element driven by said driving means and movable into and out of the path of rotational travel of said impact receiving element for respective engagement with and disengagement from said impact receiving element, fluid pressure actuated means having a relatively large area over which fluid under pressure may act to cause it to move said impact delivery element out of the rotary path of travel of said impact receiving element and also a relatively small area over which fluid under pressure may act to cause it to act to move said impact delivery element into the rotary path of travel of the impact receiving element, valve means operative to one position to subject the piston of large area to the pressure of fluid to cause said fluid pressure actuated means to act to move said impact delivery element out of the path of travel of the impact receiving element, said valve means being operative to another position for cutting off the flow of fluid to the piston of larger area and for venting the fluid under pressure acting on the piston of larger area to render the fluid pressure actuated means responsive to move said impact delivery element into the path of travel of the impact receiving element, and centrifugal means operative to control the operation of said valve means.

10. A rotary impact tool comprising a frame, a rotatable work member and rotatable driving means therefor mounted on said frame for rotation relative to the frame, an impact receiving element through which torque forces may be transmitted to said work member, an impact delivery element driven by said driving means and movable into and out of the path of rotational travel of said im-

pact receiving element for respective engagement with and disengagement from said impact receiving element, fluid pressure actuated means having a relatively large area over which fluid under pressure may act to cause it to move said impact delivery element out of the rotary path of travel of said impact receiving element and also a relatively small area over which fluid under pressure may act to cause it to act to move said impact delivery element into the rotary path of travel of the impact receiving element, valve means operative to one position to subject the piston of large area to the pressure of fluid to cause said fluid pressure actuated means to act to move said impact delivery element out of the path of travel of the impact receiving element, said valve means being operative to another position for cutting off the flow of fluid to the piston of larger area and for venting the fluid under pressure acting on the piston of larger area to render the fluid pressure actuated means responsive to move said impact delivery element into the path of travel of the impact receiving element, and means responsive to the speed of said rotatable driving means for actuating said valve means to one of its control positions and being operative upon reduction in the speed of rotary motion of the driving means for actuating the valve means to its other control position.

11. A rotary impact tool comprising a frame, a rotatable work member and rotatable driving means therefor mounted on said frame for rotation relative to the frame, an impact receiving element through which torque forces may be transmitted to said work member, an impact delivery element driven by said driving means and movable into and out of the path of rotational travel of said impact receiving element for respective engagement with and disengagement from said impact receiving element, fluid pressure actuated means for actuating said impact delivery element, centrifugally controlled valve means operative according to the rotational speed of said driving means for controlling the pressure of fluid acting on said fluid pressure actuated means and thereby controlling the operation of the fluid pressure responsive means, and fluid bias means continually exerting a bias force on said valve means in the direction opposite to the direction of centrifugal force on said valve means to move said valve means when said impact delivery element is substantially stalled.

12. In a rotary impact tool having a fluid pressure driving motor and a source of fluid under pressure for operating the same; a rotatable output shaft having impact receiving surface means, a rotatable hammer assembly having impact delivering surface means driven by said motor for intermittent engagement with said impact receiving surface means to deliver a rotary impact blow, expandable fluid pressure chamber means connected to said source of fluid, centrifugally operable valve means mounted for rotation with said hammer means for controlling the fluid pressure in said chamber means and operable to decrease pressure in said chamber means when said hammer assembly rotates at a given high speed and operable when said hammer assembly is substantially stalled to increase fluid pressure in said chamber means to cause said chamber means to expand to establish a disengaging force, and a reciprocable member connected to at least one of said impact surface means responsive to the expansion of said chamber means to cause relative disengaging motion between said impact surface means, and means exerting a continuous engaging force on said reciprocable member in a direction opposite to the direction of said disengaging force and of a magnitude less than the peak magnitude of said disengaging force.

13. In a rotary impact tool having a fluid pressure driving motor and a source of pressure fluid for operating the same; a rotatable output shaft having impact receiving surface means, a rotatable hammer assembly having impact delivering surface means driven by said motor for intermittent engagement with said impact receiving surface means to deliver a rotary impact blow, a reciprocable member connected to one of said impact surface means to cause relative engaging and disengaging motion between said impact surface means, first fluid pressure chamber means connected to said source of pressure fluid and exerting a continuous force on said reciprocable member in one direction, second fluid pressure chamber means connected to said source of pressure fluid to urge said reciprocable member in the opposite

direction, and means operating automatically in response to changes in the speed of rotation of said hammer assembly to vary the force exerted by said second fluid pressure chamber means from a magnitude exceeding the magnitude of said continuous force to a magnitude less than that of said continuous force, and thereby reciprocate said reciprocable member.

14. In a rotary impact tool having a fluid pressure driving motor and a source of fluid under pressure for operating the same; a rotatable output shaft having impact receiving surface means, a rotatable hammer assembly having impact delivering surface means driven by said motor for intermittent engagement with said impact receiving surface means to deliver a rotary impact blow, a reciprocable member connected to one of said impact surface means to cause relative engaging and disengaging motion between said impact surface means, pressure means exerting a continuous force on said reciprocable member to move said reciprocable member in one direction, fluid pressure means connected to said source of fluid under pressure and capable of exerting a force of magnitude greater than the magnitude of said continuous force and in a direction opposite to the direction of said continuous force, and centrifugally operated control means mounted for rotation with said hammer assembly for controlling said fluid pressure means to cause the force exerted by said fluid pressure means to periodically overcome said continuous force to periodically move said reciprocable member in the opposite direction.

15. In a rotary impact tool having a fluid pressure driving motor and a source of pressure fluid for operating the same; a rotatable output shaft having impact receiving surface means, a rotatable hammer assembly having impact delivering surface means driven by said motor for intermittent engagement with said impact receiving surface means to deliver a rotary impact blow, a reciprocable member connected to one of said impact surface means to cause relative engaging and disengaging motion between said impact surface means, spring means continuously urging said reciprocable member in a direction to cause said impact surface means to engage thereby to substantially stall said tool, fluid pressure means connected to said source of fluid pressure always urging said reciprocable member in the opposite direction to cause disengagement of said impact surface means thereby to cause said hammer assembly to rotate at an increased speed, the pressure of said fluid at the location of said reciprocable member varying from a high pressure when said hammer assembly is substantially stalled to a low pressure when said hammer assembly is rotating at said increased speed, the force exerted by said fluid on said reciprocable member when said hammer assembly is substantially stalled being sufficient to compress said spring and move said reciprocable member to cause disengagement of said impact surfaces, and the force exerted by said fluid on said reciprocable member when said hammer assembly is rotating at said increased speed being insufficient to overcome the force exerted on said reciprocable member by said spring means thereby causing said reciprocable member to move and cause engagement of said impact surface means.

16. In a rotary impact tool having a fluid pressure driving motor and a source of fluid under pressure for

operating the same; a rotatable output shaft having an impact receiving anvil surface spaced from the axis of rotation thereof, an impact delivering element rotatable about said axis and movable into and out of the path of said anvil surface, means for moving said element alternately into and out of the path of said anvil surface including fluid pressure means connected to said source of fluid for urging said element in one direction, a valve for controlling said fluid pressure means, centrifugal means rotatable with said motor urging said valve in one direction, bias means urging said valve in the opposite direction, said centrifugal means and said bias means providing a net force on said valve in one direction at a predetermined high speed of said motor which increases with movement of said valve in the direction of the net force to effect movement of said valve to a position causing movement of said element into the path of said anvil surface, and a net force in the opposite direction at a predetermined lower speed to effect movement of said valve in the opposite direction causing movement of said element out of the path of said anvil surface.

17. In a rotary impact tool having a fluid pressure driving motor and a source of fluid under pressure for operating the same, a rotatable output shaft having an impact receiving anvil surface spaced from the axis of rotation thereof, an impact delivering element rotatable about said axis and movable into and out of the path of said anvil surface, means for moving said element alternately into and out of the path of said surface including fluid pressure means connected to said source of fluid for urging said element in one direction, a valve for controlling said fluid pressure means, actuating means exerting a force varying with the speed of said motor on said valve urging the same in one direction, bias means urging said valve in the opposite direction, said actuating means and said bias means providing a net force on said valve in one direction at a predetermined high speed of said motor which increases with movement of said valve in the direction of the net force to effect movement of said valve in a direction to cause movement of said element into the path of said anvil surface, and a net force in the opposite direction at a predetermined lower speed to effect movement of said valve in the opposite direction to cause movement of said element out of the path of said anvil surface.
